Primary Examiner — S. Bryan Reinholdt, Jr.*Assistant Examiner* — Loryn K. Leblanc(74) *Attorney, Agent, or Firm* — Edward Darius Robinson(57) **CLAIM**

The ornamental design for a stabilizer gimbal as shown and described.

DESCRIPTION

FIG. 1 is a front, left and bottom perspective view of a stabilizer gimbal, showing my new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 1; and,

FIG. 12 is an enlarged view of detail 12 in FIG. 2.

The dashed broken lines depict portions of the stabilizer gimbal that form no part of the claimed design.

The dot-dash broken lines in FIGS. 1, 2 and 9–12 depict the boundaries of the enlarged views and form no part of the claimed design.

1 Claim, 12 Drawing Sheets(56)
